UNITED STATES PATENT OFFICE.

BENJAMIN F. AUFDERHEIDE, OF DAVENPORT, IOWA, ASSIGNOR OF ONE-HALF TO
WILLIAM F. YOUNG, OF DAVENPORT, IOWA.

WINDOW STOPLOCK.

Application filed April 18, 1924. Serial No. 707,331.

To all whom it may concern:

Be it known that I, BENJAMIN F. AUFDERHEIDE, a citizen of the United States, residing at Davenport, in the county of Scott and State of Iowa, have invented a new and useful Window Stoplock, of which the following is a specification.

My invention relates to improvements in window stop-locks, which are secured upon a window sash, and are commonly used to contact upon the corresponding upper or lower sash of a window having two or more sashes, but may be used in windows having only a single sash, and the objects of my invention are, first, to provide a means of locking a pair of window sashes at any given place with a single lock; second, to provide a window locking means more difficult for a burglar to release; and third, to provide a window lock of more practical and ornamental utility, at a more economic utility.

I attain these objects by the mechanism illustrated in the accompanying drawings, in which—

Figure 1 is a side view of the stop-lock; Fig. 2, a front view of the stop-lock mounted with broken portions of a top and bottom sash of a window, disclosing the manner of attaching the stop-lock to the window frame and its working between the two sashes, also disclosing pot hole plates attached to a member of one of said sash frames for such purpose; Fig. 3, a plan view in cross section of the stop-lock complete, mounted on broken portions of an upper and a lower window sash frame, taken on line "a"—"a" of Figure 1; Fig. 4 a front end view of the stop-lock; Fig. 5, a side view in perspective of the inner sleeve; Fig. 6, a side view in perspective of the shaft; Fig. 7, a side view in perspective of the sleeve hub; Fig. 8, a side view in perspective of the cap washer; Fig. 9, a side view in perspective of the thimble cap; Fig. 10, a side view in perspective of the plunger; and Fig. 11, a side view in perspective of a broken portion of the thimble.

Similar numerals refer to similar parts throughout the several views.

Shaft 7, having a journaled end portion 7^a, and a tapering journaled spring seat portion 7^b forms the framework of the stop-lock. Upon the journaled end 7^a of shaft 7, by means of a pin 15 inserted connectedly through transverse holes 8^d of sleeve

nut 8 and hole 7^c of shaft 7, I securely mount 55 sleeve nut 8. Sleeve nut 8 corresponds in length to about one half the length of said journaled portion 7^a of shaft 7, and in diameter is suitably larger than the body 7^b of shaft 7, to workably accommodate the thickness of the spirals of spiral spring 10, which 60 spiral spring 10 is mounted encircling the tapering journaled spring seat portion 7^b of said shaft 7, which tapering journaled spring seat portion 7^b has a diameter at the 65 end of journaled portion 7^a corresponding to the diameter of end portion 7^a, but which tapers for a distance corresponding to the uncompressed length of spring 10, until it reaches the flanged end wall 7^d of end 7^a. 70 Said spiral spring 10 is secured between sleeve nut 8 and sleeve 9, by being secured at one of its ends to said sleeve nut 8, by means of the right angularly bent end 10^a of 75 said spring, which is inserted in a longitudinal hole 8^c provided therefor in the transverse end surface of said sleeve nut 8, the other end 10^b of said spiral spring 10, being also bent right angularly and is inserted in a longitudinal hole 9^a provided therefor in 80 the transverse surface of the end of sleeve 9.

Sleeve 9 is loosely installed on the other end 7^d of shaft 7, for the purpose of so connectedly attaching said spiral spring 10 between sleeve nut 8 and sleeve 9, being to securely hold the ends 10^a and 10^b of spring 10 so that it may be tightened by turning shaft 7 upon which sleeve nut 8 is mounted; and the purpose of providing the tapering journaled spring seat 7^b portion of shaft 7, for 85 said spring 10, is to facilitate quick and powerful action in releasing spring 10, and to avoid any tendency in the spring 10 to bind or rub against thimble 3, by giving the 90 spring 10 more room for action. 95

I mount thimble 3 upon shaft 7, over all, and hold it in place, with its front end 3^c installed upon sleeve nut 8, coactingly upon the journaled portion 8^a and the ribbon band 8^b formed integral around, and spaced suitably between the ends of sleeve nut 8, and adapted to loosely fit in the boxed entrance to the center hole 4^b of cap washer 4, and the boxed center hole 3^d of the said thimble 3, 100 said sleeve nut 8 being mounted on the 105 journaled end 7^a of shaft 7; the rear end 3^e of thimble 3 is installed on sleeve 9, which is installed on the rear 7^d of shaft 7.

Suitably distanced from and upon the horizontal surface of the end 7^a of shaft 7, a guide pin 12 is installed in a transverse hole 7^e provided in said shaft 7, which pin is 5 of a length corresponding to the thickness of said inner sleeve 9, and is for the purpose of forcing sleeve 9 inward or outward within thimble 3, by the sliding action of the pin 12 upon the angling walls, of a spiral slot 9^e provided in the walls of sleeve 9, which action is caused by the rotary movement of shaft 7 within thimble 3, whereby the spiral spring 10 is compressed or relaxed as desired, and sleeve 9 is thus drawn 10 within thimble 3 inwardly or forced outwardly upon shaft 7. Guide pin 12 is also used for the purpose of locking the sleeve 9 with spiral spring 10 in compressed position, when sleeve 9 is fully drawn within 15 thimble 3, and spring 10 is fully compressed. To facilitate the locking of sleeve 9 in the winding of spring 10, spiral slot 9^e is provided with right angularly flanged shoulders 9^f and 9^g, suitable for engaging the sleeve 9 upon pin 12 when the end 9^b of the spiral slot 9^e is reached by the turning of shaft 7 within sleeve 9 and thimble 3. The enlarged end 9^b of slot 9^e is longitudinally elongated, and the shoulders 9^f and 9^g are rounded for the 20 purpose of facilitating a smooth movement of the pin 12 in and out of the said enlarged end 9^b.

Sleeve 9 has holes 9^e transversely disposed through its walls, positioned near one 35 of its ends through which a pin 13 is connectedly inserted through a transverse hole 11^b provided in the journaled end 11^c of plunger point 11 when said journaled portion 11^c is inserted in sleeve 9, thus leaving 40 plunger tip 11^a fitting over the end of sleeve 9 flush, said tip 11 being for the purpose of engaging in the hole 18^a of plate 18, provided in one of the window sash frames in connection with which the stop-lock is to 45 be used.

Pin 13 is secured in holes 9^e of sleeve 9, and hole 11^b of plunger point 11, and is made suitably long to permit its protruding ends to engage in the bifurcations 3^b, provided on either side of thimble 3. Bifurcations 3^b provided on either side of thimble 3, provide vibrating space for pin 13, and are for the purpose of preventing sleeve 9 from rotating within thimble 3, when sleeve 9 is caused to slide in and out of thimble 3 by the movement of pin 12 in spiral slot 9^e caused by the turning of shaft 7.

Cap washer 4 is mounted loosely with its reamed boxing 4 in contact with band 8^b on short journaled end 8^c of sleeve nut 8, when said sleeve nut 8 is mounted upon the journaled end 7^a of shaft 7. Cap washer 4 is connectedly secured to the flange 3^a of thimble 3 by screws inserted in holes 3^c, thus creating a closed boxing, in which the

ribbon band 8^b of sleeve nut 8 is made to revolve by journal cap 5 or handle 6, attached to shaft 7 and by spiral spring 10.

Having mounted cap washer 4, and secured the same to the flange 3^a of thimble 3, I mount journal cap 5 upon the journaled end 7^a of shaft 7, through horizontally disposed hole 5^a securing the same snugly against cap washer 4 by pin means inserted connectedly through transverse hole 5^b of the journal cap 5 and a transverse hole 7^e in the said journaled end 7^a of shaft 7.

Journal cap 5 is suitably larger than the hole 4^c of cap washer 4, for the purpose of rendering the boxing 4^b—3^a dust proof, and said cap 5 also serves as a thumb nut with which to operate the stop lock, but in my preferred form I attach a handle 6 in longitudinal grooves 5^c upon surface of journal cap 5 by which I turn the shaft, and thus draw the plunger 11 into thimble 3, or release it.

I claim:

1. In a stop-lock a shaft having a journaled end portion, suitable for mounting thereon, in order named, a sleeve cap, and a thimble cap, said journaled end portion being provided with transverse hole means suitable for the engagement of pin means provided for securing said sleeve cap and said thimble cap thereon, said shaft also having disposed between its ends a tapering journaled portion suitable for installing thereon a spiral spring; one of the ends of said shaft being of the same diameter of the larger end of said tapering portion, said shaft end having right-angularly protruding from the annular surface thereof a pin, suitable to move unobstructedly within a slot provided in a sleeve to be mounted movably on said shaft.

2. In a stop-lock having a shaft, a sleeve cap member suitably larger in diameter than said shaft, mounted on the journaled end of said shaft, said sleeve cap having transverse hole means suited for connectedly securing the same by pin means upon the journaled end of said shaft, said sleeve cap having disposed between its ends ribbon band means constructed integral therewith, suited to fit within split boxing means provided in the end of a cap washer and the flanged end of a thimble, said ribbon band positioned on said sleeve cap nearer one of the ends of said sleeve cap than the other, said transverse hole means being positioned transversely through the said sleeve cap on the side of said ribbon band disclosing the longer end of said sleeve cap, a linearly disposed hole disposed in the longer end of said sleeve cap suited to receive the right angularly bent end of a spiral spring, said hole being disposed near the larger diameter of its perimeter.

3. In a stop-lock having a shaft provided

with a sleeve cap securely mounted on one of its ends; a spiral spring mounted on a tapering journaled portion of said shaft, said spiral spring having one of its ends 5 right angularly bent, one of said ends being secured in a linearly disposed hole provided therefor in one of the transverse ends of said sleeve cap, the other right angular end of said spiral spring being secured in 10 a linearly disposed hole provided therefor in one of the transverse ends of a sleeve disposed on one of the ends of said shaft, said spiral spring being capable of being compressed upon said tapering journaled portion of said shaft by the action of said sleeve thereon.

4. In a stop-lock having a shaft provided with one journaled end and a tapering journaled spring seat middle portion, said journaled end supporting a sleeve nut unto which is secured a spiral spring co-actingly secured upon said shaft between said sleeve nut and a sleeve; said sleeve being slideably secured upon one of the ends of said shaft 25 by pin means, said sleeve being provided with a spiral slot in its wall, said slot being suitable to slideably engage a pin connecting means provided upon the rotund surface of one of the ends of said shaft, said slot having one of its ends elongatingly enlarged linearly with said sleeve suitable to form hook means to retentively hold the sleeve suspended with said pin in the enlarged end of said slot with said spiral 30 spring compressed, said enlarged end having its shoulders rounded in such way as to facilitate the free movement of said sleeve on said pin engagingly or disengagingly from said spiral slot to said enlarged end of 35 said slot, transverse hole means provided in one of the ends of said sleeve, suitable to engage pin attachment means provided for securing a plunger inserted in the end of said sleeve linearly disposed hole means provided in the transverse end wall of the other end of said sleeve, suitable to engagingly receive the right angularly bent end 40 of a spiral spring, a plunger secured by pin means in the end of said sleeve nearest the enlarged end of said spiral slot, said pin means extending beyond the walls of said sleeve suitable to slideably engage in bifurcations provided in the skirt of a thimble in which said sleeve is slideably installed.

45 5. In a stop-lock having a shaft a sleeve cap mounted on one end thereof, a sleeve mounted on the other end thereof, a spiral spring connectedly attached between them; a thimble having one of its ends flanged, a right angular boxing provided in the center 50 of said flanged end of said thimble, screw holes provided in said flange, said thimble having the skirt of its other end provided upon either side with a bifurcation suitable 55 for slideably engaging with pin means pro-

truding from the sides of said sleeve mounted upon said shaft, said thimble being suitable to admit said spiral spring to expand and contract upon said shaft within it, and to permit said sleeve to slideably move within it, said thimble also being suitable when connectedly secured to a cap washer secured to it by screw means inserted in the screw holes provided in its flange, to prevent the sleeve installed therein from revolving with 70 said sleeve cap installed therein.

6. In a stop-lock having a shaft, a sleeve hub securely mounted on one end thereof, a sleeve mounted on the other end thereof, a spiral spring connectedly attached between them, a thimble having one of its ends flanged, a center hole suited to fit over a sleeve cap, a right angular boxing provided in the center hole of said flanged end of said thimble, screw holes provided in said flange; a cap washer of a diameter corresponding to the diameter of the flange of said thimble, its center hole suitable to fit upon the short journaled end of said sleeve hub, a right angular boxing provided in 80 said center hole of said cap washer, suitable to engage upon the ribbon band provided upon the said sleeve hub, suitable screw hole means transversely provided in the rim of said cap washer corresponding to 85 like screw hole means provided in the flange of said thimble, suitable to permit said washer to be secured by screw means to said flange of said thimble, said washer suitable when secured to said flange of the end of 90 said thimble to form a complete boxing for said sleeve cap, to facilitate the turning of said shaft and to prevent lateral movement in said shaft.

7. In a stop-lock having a shaft, said shaft having one of its extremities journaled, its other end supporting a vertically disposed pin, a sleeve hub securely mounted on one end thereof, a sleeve mounted on the other end thereof, operating by slot means upon 95 said vertical pin, a spiral spring connectedly attached between them, a thimble having one of its ends flanged, screw holes provided in said flange, a center hole and boxing in said thimble, said center hole suited to fit over one end of a sleeve, a cap washer of a diameter corresponding to the diameter of said flanged end of said thimble, said cap washer having a center hole and boxing, said center hole being of a size suited to fit over 100 the end of said sleeve hub in such manner as to be capable of being securely attached through hole means provided in its face by screw means to said flanged end of said thimble; a thimble cap in diameter larger than the diameter of said sleeve hub mounted securely by center hole and transverse hole and pin upon the journaled end of said shaft flush against the end of said sleeve hub 105 loosely touching said cap washer, said thim-

119 115 120 125 130

ble cap having a handle member attached thereto by side groove means, said thimble cap suited to protect said boxing from dust and dirt, to turn said shaft in such manner as to compress said spiral spring to drive the pin provided in the other end of said shaft along the channel of said spiral slot, thus drawing said sleeve containing said plunger point within said thimble, to the point of securing the said sleeve in the enlarged head

of said slot upon the pin provided in the end of said shaft, all for the purposes specified.

Done at Davenport, in the county of Scott and State of Iowa, this 16th day of April, A. D. 1924.

BENJAMIN F. AUFDERHEIDE.
